UNITED STATES PATENT OFFICE.

GEORGE W. WALLACE, OF EAST ST. LOUIS, ILLINOIS, ASSIGNOR, BY MESNE ASSIGNMENTS, TO WALLACE COKE, OIL AND BY-PRODUCTS COMPANY, OF EAST ST. LOUIS, ILLINOIS.

APPARATUS FOR RECOVERING OIL FROM OIL-SHALE AND OTHER CARBONACEOUS MATERIALS.

1,283,000.

Specification of Letters Patent. Patented Oct. 29, 1918.

Application filed February 8, 1918. Serial No. 215,971.

To all whom it may concern:

Be it known that I, GEORGE W. WALLACE, a citizen of the United States, residing at East St. Louis, Illinois, have invented a certain new and useful Improvement in Apparatus for Recovering Oil from Oil-Shale and other Carbonaceous Materials, of which the following is a full, clear, and exact description, such as will enable others skilled in the art to which it appertains to make and use the same.

This invention relates to an apparatus for recovering oil from oil shale, bituminous coal and other carbonaceous materials.

The main object of my invention is to provide a practicable apparatus of simple design in which oil shale, bituminous coal and other carbonaceous materials can be distilled successfully so as to effect the recovery of the oil contained in same.

Another object is to provide an apparatus for the purpose described, which is so constructed that the parts of the retorts which require frequent cleaning and also the parts of the retorts which are opened to effect the discharge of the residue from same are moved into and out of operative position by a mechanism of simple design that is arranged above the retorts, thereby simplifying the construction of the apparatus and making it possible to provide the apparatus with an unobstructed pit or chamber beneath the retorts into which cars or trucks can be run so as to receive the residue discharge from the retorts.

And still another object of my invention is to provide a distilling apparatus for carbonaceous materials that consists of a vertically-disposed retort sealed at its upper and lower ends and having arranged at the center of same a perforated take-off duct whose lower end communicates with a pipe that leads to a suction-producing device, thereby insuring the recovery or collection at the same point of both the oil and the gases evolved in the distilling operation, the suction pipe being preferably connected to the lower end of the retort or take-off duct in such a manner that said pipe can be disconnected and moved into an inoperative position when it is desired to discharge the contents of the retort or withdraw the take-off duct from same.

Figure 1 of the drawings is a vertical sectional view of an apparatus constructed in accordance with my invention.

Fig. 2 is a top plan view of said apparatus, partly in horizontal section on the line 2—2 of Fig. 1.

Fig. 3 is a vertical sectional view of the regenerator of the apparatus, taken on the line 3—3 of Fig. 1.

Fig. 4 is an enlarged vertical sectional view of one of the retorts, taken on the line 4—4 of Fig. 1.

Fig. 5 is a bottom plan view of the retort shown in Fig. 4.

Fig. 6 is a vertical sectional view, illustrating a slight modification of my invention; and

Fig. 7 is a horizontal sectional view, taken on the line 7—7 of Fig. 6.

Referring to the drawings which illustrate the preferred form of my invention, A designates a plurality of vertically-disposed retorts that are adapted to be filled with oil shale, bituminous coal or other carbonaceous material that contains oil, said retorts being arranged above a pit or chamber B into which cars or trucks C can be run to receive the residue that is discharged from the retorts, as hereinafter described. Any suitable means can be used for heating the retorts A, but I prefer to provide the apparatus with a heating means consisting of a gas producer D and a regenerator E combined in such a manner that when the apparatus is in operation jets of gas and highly heated air will be supplied through ports a and b to combustion chambers x that surround the retorts A, the products of combustion which escape from the combustion chambers x traveling through the regenerator E, and thus heating the air that is supplied to the combustion chambers through the ports b.

Each of the retorts A preferably consists of a cylindrical-shaped metal shell 1 tapered slightly from its lower toward its upper end and having its upper end sealed or cut off from the atmosphere by means of a removable cover 2 and its lower end sealed or cut off from the atmosphere by a removable bottom plate 3. A take-off duct F consisting of a perforated member of cylindrical form is arranged at the center of the retort and extends upwardly through same

to a point in proximity to the cover 2 that closes the upper end of the retort, said take-off duct being connected in any suitable manner to the bottom plate 3, as, for example, by means of bolts or fastening devices 4 that pass through said bottom plate and through a flange at the lower end of the take-off duct, as shown in Fig. 4. The take-off duct F is preferably of uniform diameter throughout its entire length so that the annular space between the exterior of same and the interior of the shell 1 that receives the material being distilled, will diminish gradually in cross-sectional area from its lower toward its upper end, thereby causing the heat to penetrate through the material in the retort substantially uniformly, owing to the fact that the thickness of the body of material at the lower end of the retort, where the heat is most intense, is greater than the thickness of the body of material at the upper end of the retort, where the temperature is lower. The take-off duct F is provided at its upper end with a removable, dome-shaped top portion f, and the side walls of the take-off duct are provided with numerous orifices y, as shown in Fig. 4, through which the oils and gases evolved in the distilling operation are drawn inwardly into the take-off duct by the suction produced by a suction device that is connected to the lower end of the take-off duct. In the form of my invention herein shown the take-off duct F is arranged in vertical alinement with a hole 5 in the bottom plate 3 of the retort, and a suction pipe 6 that leads to a suction-producing device, is detachably connected to the bottom plate 3 at a point in alinement with the hole 5 therein. It is immaterial, so far as my invention is concerned, how the suction pipe 6 is detachably connected to the bottom plate 3 of the retort, but I prefer to form said suction pipe in sections, the top section 6^a being permanently connected to the bottom plate, as shown in Fig. 4, and detachably connect said sections together by bolts or other suitable fastening devices 6^b, thus enabling the lower section of the suction pipe to be disconnected from the upper section of the pipe and moved into such a position that it does not interfere with the downward movement of the bottom plate 3 of the retort. The shell 1 of each retort is provided at its lower end with laterally-projecting brackets 7 that rest upon supporting elements 8, preferably I-beams that span the pit or chamber B underneath the retorts, and the removable bottom plate 3 of the retort is retained in operative position, as shown in Fig. 4, by means of eye bolts 9 pivotally connected to the brackets 7 and provided with nuts 9^a that are positioned underneath the bottom plate 3. Said bottom

plate can either be provided with holes through which bolts 9 pass, or said plate can be provided at its periphery with bifurcated lugs 9^b so as to enable the bolts to be swung into and out of engagement with the bottom plate without removing the nuts 9^a on said bolts. The cover 2 of the retort is also preferably retained in operative position by pivotally mounted eye bolts 9.

The bottom plates 3 of the retorts are adapted to be moved downwardly so as to effect the discharge of the residue from the retorts and to completely withdraw the perforated take-off ducts from the retorts for cleaning, by means of an overhead hoisting mechanism that is arranged above the retorts. Various kinds of hoisting mechanisms can be used for this purpose, but I prefer to use a hoisting mechanism that consists of a movable frame G arranged above the retorts and provided with a pulley 10 over which a cable 11 passes. When it is desired to discharge the contents of one of the retorts the cover 2 of said retort is first removed and thereafter a hook 14 on the cable 11 is hooked into an eye 12^a on a long rod 12 whose lower end is connected to a portion 13 on the bottom plate 3 of the retort. After the suction pipe 6 has been disconnected and moved into the position shown in broken lines in Fig. 5 and the bottom plate 3 disconnected from the retort, the cable 11 is slackened off, so as to lower the bottom plate 3, and thus permit the residue to escape from the retort into a car C 100 in the chamber B. If it is desired to clean the take-off duct F, the bottom plate 3 is moved downwardly far enough to completely withdraw the take-off duct from the retort. To restore the bottom plate and take-off duct to their former position it is only necessary to pull on the cable so as to move the bottom plate upwardly, and thereafter secure said bottom plate in operative position by means of the eye bolts 9. After the retort has been filled with the material to be distilled, the cover 2 is arranged in operative position so as to seal the upper end of the retort.

By constructing the apparatus in the manner above described, I am able to use a mechanism of simple form for discharging the retorts and withdrawing the take-off ducts from same, and I am also able to provide the apparatus with an unobstructed pit or chamber under the retorts into which cars can be run to receive the residue from the retorts and in which the operators can stand while cleaning the take-off ducts. Still another desirable feature of such an apparatus is that the oil, as well as the gases that are evolved during the distilling operation, are recovered or collected at the same point, owing to the fact that gravity causes the oil which enters the take-off duct to flow downwardly

115

through same into the suction pipe 6 through which the gases are withdrawn from the retort. The fact that the space between the take-off duct and the shell 1 of the retort is sealed at its upper and lower ends insures the gases traveling through the coolest portion of the retort, namely, inwardly into the center take-off duct, in escaping from the retort. Consequently, all of the gases and vapors start to cool and condense immediately after they have been formed and remain in this condition in escaping from the retort. While I have herein illustrated my invention embodied in an apparatus provided with a plurality of retorts, it will, of course, be understood that my broad idea is applicable to an apparatus provided with a single retort. In a multiple retort apparatus, as herein shown, it is preferable to equip the apparatus with a suction manifold 6^c, as shown in Fig. 2, provided with a number of branches 6^a, each of which has a plurality of suction pipes 6, each of the pipes 6 being so constructed that it can be swung horizontally out of vertical alinement with the retort with which it cooperates when it is desired to lower the bottom plate of the retort.

When treating certain kinds of substances or materials it is desirable to introduce steam into the retorts so as to increase the nitrogenous compounds and also assist in the removal of the lighter hydrocarbons. The steam can be injected into the retorts in various ways, but one convenient way of accomplishing this is illustrated in Figs. 6 and 7 of the drawings which illustrate a retort whose bottom 3 is provided with a plurality of vertically-disposed steam pipes 15 that project upwardly into the shell 1 of the retort, said pipes having orifices through which jets of steam escape. The lower ends of the pipes 15 communicate with a header 16 on the bottom plate 3 of the retort and the upper ends of said pipes are connected to laterally-projecting brackets 17 on the take-off duct F. In view of the fact that said steam pipes are carried by the bottom plate 3 they are withdrawn from the retort when said bottom plate is moved downwardly.

Having thus described my invention, what I claim, and desire to secure by Letters Patent, is:

1. An apparatus for the purpose described, provided with a vertically-disposed retort that is sealed at its upper and lower ends, a perforated take-off duct arranged inside of said retort at the center of same, and a suction pipe communicating with the lower end of said take-off duct.

2. An apparatus for the purpose described, provided with a vertically-disposed retort that is sealed at its upper and lower ends, a perforated take-off duct arranged in-

side of said retort at the center of same, and a suction pipe communicating with the lower end of said take-off duct, the side wall of said retort being tapered from its lower toward its upper end and said take-off duct 70 being of tubular form and of the same diameter throughout the major portion of its length; for the purpose described.

3. An apparatus for the purpose described, provided with a vertically-disposed 75 retort that is sealed at its upper and lower ends, a perforated take-off duct arranged inside of said retort at the center of same, and a suction pipe communicating with the lower end of said take-off duct, said retort 80 and take-off duct being of cylindrical form and the take-off duct being closed at its upper end.

4. An apparatus for the purpose described, provided with a vertically-disposed retort 85 that is sealed at its upper and lower ends, a perforated take-off duct arranged inside of said retort at the center of same, and a suction pipe communicating with the lower end of said take-off duct, said take-off duct 90 consisting of a cylindrical-shaped member provided with orifices and having its upper end closed by a dome-shaped portion.

5. In an apparatus of the character described, a vertically-disposed retort, a removable bottom plate that forms a closure for the lower end of said retort, a perforated take-off duct carried by said bottom plate, and a suction pipe arranged under said bottom plate in communication with the lower end 100 of said take-off duct and adapted to be swung laterally so as to permit said bottom plate to move downwardly.

6. In an apparatus of the character described, a cylindrical-shaped metal shell tapered from its lower toward its upper end, a cylindrical-shaped, perforated take-off duct of uniform diameter arranged inside of said shell, a removable cover at the upper end of said retort, and a removable bottom plate 110 at the lower end of said retort, the take-off duct being mounted on said bottom plate, pivotally mounted devices on the retort for securing said cover and bottom plate in position, and a suction pipe detachably connected to said bottom plate and communicating with the lower end of said take-off duct.

7. An apparatus of the character described, provided with a vertically-disposed retort 120 equipped with a removable bottom plate, a perforated take-off duct arranged inside of said retort and having its lower end communicating with a suction pipe, and means arranged above the retort for lowering and 125 raising said bottom plate.

8. In an apparatus of the character described, a vertically-disposed retort sealed at its upper and lower ends and provided with a perforated take-off duct whose lower 130

end communicates with a suction device, a pit or chamber arranged underneath the retort, and means arranged above the retort for discharging the contents of same into 5 said pit and withdrawing said take-off duct from the retort.

9. In an apparatus of the character described, a vertically-disposed retort provided with a removable bottom plate, a perforated 10 take-off duct mounted on said bottom plate and projecting upwardly into the retort, a hoisting mechanism arranged above the retort, and a device connected to the bottom plate of the retort that forms a connection 15 between said plate and hoisting mechanism.

10. An apparatus for the purpose described, comprising a plurality of vertically-disposed retorts, each of which is provided with a removable bottom plate, perforated

take-off ducts in the retorts mounted on said 20 bottom plates, means for heating the retorts, a pit or chamber underneath the retorts, suction pipes in said pit detachably connected to the lower ends of the take-off ducts of the retorts, and means above the retorts for 25 lowering said bottom plates into said pit.

11. In an apparatus of the character described, a retort whose upper end is sealed, a removable bottom plate that forms a closure 30 for the lower end of said retort, a perforated take-off duct carried by said bottom plate and having its lower end connected with a suction producing device, and devices carried by said bottom plate and projecting 35 upwardly into the retort for supplying steam to same.

GEORGE W. WALLACE.
